UNITED STATES PATENT OFFICE

MARY ELLEN WETHERELL, OF ROXBURY, MASSACHUSETTS

DESIGN FOR AN IDENTIFICATION CARD HOLDER

Application filed April 4, 1933. Serial No. 47,685. Term of patent 14 years.

To all whom it may concern:

Be it known that I, MARY E. WETHERELL, a citizen of the United States, residing at Roxbury, in the county of Suffolk, and State of Massachusetts, have invented a new, original, and ornamental Design for an Identification Card Holder, of which the following is a specification, reference being had to the accompanying drawing, forming part thereof.

I claim:—

The ornamental design for an identification card holder as shown.

MARY ELLEN WETHERELL.
